UNITED STATES PATENT OFFICE

ARTHUR LIONEL MANNING, OF OAK PARK, ILLINOIS, ASSIGNOR TO WESTERN ELECTRIC COMPANY, INCORPORATED, OF NEW YORK, N. Y., A CORPORATION OF NEW YORK

APPARATUS FOR SECURING AND BRACING ARTICLES FOR TRANSPORTATION

Application filed July 24, 1928. Serial No. 295,093.

This invention relates to an apparatus for securing and bracing articles for transportation, and more particularly to an apparatus for securing for transportation as a substantially unitary mass a group of articles.

This invention is particularly applicable to the shipping of completely assembled loading coils used in connection with telephone systems. This type of coil is mounted in a comparatively heavy upright iron case having projecting from its upper end cover a flexible, coiled cable stub which at its inner end is integrally united with the coil sealed in the case, the outer end of the cable stub being connected with the telephone circuit at the point of installation to which the loading coil is transported from the manufacturer. In the shipment of coils of this type the problem has been to provide a method and means offering a maximum protection to the coils from injury and damage during transit to the actual point of installation, which is economical to use and permits the coils to be handled in a facile manner either in their loading upon or unloading from the means of transportation.

The object of this invention is to provide an apparatus for securing and bracing articles for transportation which is simple, effective and economical and which may be easily and quickly constructed.

In accordance with one embodiment of the invention, a semi-circular bracket, having bifurcated ends which are attached to and arranged within the circumference of the cover of the coil case, surrounds the greater portion of and supports the coiled cable stub in a fixed relation to the case. The bifurcated ends of the bracket are fixed to the coil case at four points by bolts used in securing the cover to the case along with four removable lugs which project from the periphery of the cover and cooperate with loops of steel strapping to secure the coil case to a wooden skid. A plurality of coils individually protected and mounted in the hereinbefore described manner are banded together to form a substantially unitary mass by a plurality of horizontal steel straps encircling them. Also

encircle certain of the skids and a common horizontal wooden member which spans and rests upon the several covers, whereby relative movement of the individual coils within the banded unit is substantially eliminated and any movement of the unit as a whole upon the floor of a car or other means of transportation is reduced to a minimum.

Other objects and advantages of the invention will more fully appear from the following detailed description taken in connection with the accompanying drawings which illustrate one embodiment thereof, in which

Fig. 1 is a diagrammatic plan view of a carrier loaded with a plurality of articles assembled in multi-group formation, each group assembled and secured to form a substantially unitary mass in accordance with the features of this invention;

Fig. 2 is an enlarged detail plan view of one of the groups of articles illustrated in Fig. 1;

Fig. 3 is a side elevation thereof, partly in section;

Fig. 4 is a fragmentary end elevation looking toward the right end of Fig. 3, and

Fig. 5 is an enlarged detail view, partly in section, taken on the line 5—5 of Fig. 2.

Referring to the drawings in detail wherein like reference numerals indicate similar parts throughout the several views and in which the features of this invention are illustrated as applied to the securing and bracing of loading coils of the type hereinbefore described for transportation, and particularly to Figs. 2 and 3, there is shown a group 10 of loading coils, each coil being mounted in a comparatively heavy upright iron case 11. Although the group 10 of coil cases 11 is shown in Figs. 2 and 3 and in Fig. 1, which illustrates a plurality of groups 10 mounted on a carrier 12, for instance, a railroad freight car or a motor truck, as comprising three coils, it will be apparent that the number of coils comprising a unitary group may vary, depending on the space provided on the transportation means, the size of the individual article to be included in a group or other considerations.

Each coil case 11 is mounted on an indi-

100

vidual wooden skid 13 comprising spaced parallel runners 14 interconnected by a rectangular shaped floor 15 upon which the bottom surface of the case 11 rests. Surrounding the periphery of the coil case 11, illustrated as circular, which in some instances may be square or rectangular, adjacent the bottom surface thereof is a raised continuous guard rail 16 comprising four straight members attached to the outer portion of the floor 15 extending outside of the periphery of the case, the inner vertical faces of the rail members contacting with the peripheral surface of the case at four points, thus preventing lateral movement of the case upon the skid floor 15. As clearly illustrated in Figs. 2 and 3 the width of the runners 14 is greater than that of the guard rail 16, particularly those members thereof which extend parallel thereto, so that the weight of the case 11 at two diametrically opposite points is directly supported on the runners with the skid floor 15 intermediate.

Projecting upwardly from an upper end cover 20 of the case 11 at one side is a flexible coiled cable stub 21 which at its inner end is integrally united with the coil sealed in the case and which due to its flexibility should be maintained in a fixed relation with respect to the case, otherwise it would be liable to become damaged in transit. The cable stub 21 is supported on a semi-circular metallic bracket 22, which is arranged within the diameter of the cover 20 for a purpose which will hereinafter be referred to. The opposite ends of the bracket 22 are bifurcated and provided with a pair of outwardly extending feet 23 (Fig. 5) spaced to correspond with the spacing between adjacent bolts 24 provided for securing the cover 20 to the coil case 11. It is desirable that the bracket 22 be attachable to the case 11 and removable therefrom without loosening the securing bolts which might disturb a seal 25 (Fig. 5) between the cover 20 and the case 11. This is accomplished by providing at predetermined diametrically opposite points with respect to the cover 20 a pair of bolts 26 of extra length, four in all, one of which is clearly illustrated in detail in Fig. 5. Surrounding each of the nuts threaded on the extra length bolts 26 is a collar 27 which extends slightly above the top of the nut and upon each of the collars is positioned a lug 28 which extends radially outside the periphery of the cover 20, the purpose of which will presently be described. The bracket 22 is then mounted in position with the feet 23 thereof, which are apertured, threaded over the four bolts 26 and thereafter clamped with the lugs 28 against the collar 27. It will be apparent that the bracket 22 can thus be readily attached to and detached from the case 11 without disturbing the original securing of the cover 20 to the case 11. After

the mounting of the bracket 22 the cable stub 21 is coiled to fit the inside surface of the semi-circular portion of the bracket and then tied thereto by a binding 29 of burlap or other suitable material.

The assemblage comprising the coil case 11 with the integrally attaching cable stub 21 and its supporting bracket 22 which is of greater height than width is securely bound to the skid 13 by vertical loops of steel strapping 30, tightened and clamped in a well known manner, one strap passing around each of the lugs 28 and the projecting portions of the runners 14 as clearly shown in Figs. 2 and 3. The bottom surface of each of the runners 14 is provided with a groove 31 (Fig. 3) for the purpose of predeterminedly positioning the straps 30 with respect to the runners and to present a comparatively smooth lower surface on the runners to the floor of the carrier or other support, and to facilitate the movement of the loaded skid 13 on its support, the outer lower corners of the runners 14 are rounded or beveled in a well known manner. This completes the description of the method and means for securing for transportation an individual loading coil with its coiled cable stub 21 in fixed relation with the coil case 11 to an individual supporting skid 13.

The loading coils are individually secured and braced in the manner hereinbefore described in a shipping room or warehouse and then conveyed to the carrier 12 (Fig. 1) where they are finally arranged in two rows lengthwise of the carrier, and in groups 10, of two, three, four or five, depending on the number and size of the coils to be transported. The skids 13 are all arranged so that the runners 14 thereof extend crosswise on the carrier floor with the opposed longitudinal faces of the runners within each group substantially in abutting relation.

Each group 10 of coils is securely bound in one direction into a substantially unitary mass or group by a plurality of horizontal lengths of steel strapping 35, two straps adjacent the top and two the bottom encircling the group, the straps being spaced from the peripheral surface of each of the coils by a pair of vertical wooden spacing blocks 36 interposed between the straps 35 and the surface of the end coil case 11 of each group and upon each side of the coil, the blocks resting on the skid floor 15. The number of straps 35 tied around the cases 11 will vary with the height of the case and the number of coils to be bound into a group 10. The straps 35 are tightened and clamped in a manner similar to that employed in securing the individual coil to its skid 13 by means of the straps 30, and the straps 35 are prevented from moving on the blocks 36 after being tightened by means of staples 37 spanning the straps and driven into the blocks.

The group of coils is also bound in a direction substantially at right angles to the direction of the horizontal straps 35 by a pair of vertically extending steel straps 38 encircling the end skids 13 of the group and a horizontal wooden member 41 which spans and rests upon the several covers 20 of the cases 11. As clearly illustrated in Figs. 2 and 3 opposite portions of the straps 38 extend downwardly from the member 41 behind the upper pair of straps 35 and the looped strapping 30, outside of the lower pair of straps 35 and then under the floor 15 of the skid 13. The member 41 comprises two lengths of board nailed together after wooden blocks 42 are nailed to the bottom surface of the lower board by nails driven from the top surface thereof. The blocks 42 are attached to the member 41 and are provided with curved faces for fitting between and engaging opposed peripheral surfaces of adjacent covers 20 and cases 11 and serve to predeterminedly space the upper ends of the adjacent cases, the lower ends thereof being spaced by the opposed abutting faces of the skid runners 14. It is to be understood that the member 41 with the attached blocks is in position when the horizontally extending straps 35 are tightened and clamped as hereinbefore described. The straps 38 are prevented from moving on the member 41 after being clamped by the use of staples 43 spanning the straps 38 and driven into the member 41.

From the foregoing description it will be apparent that during transportation of the coils on the carrier 12 or other transportation means relative movement of the individual coils within a group 10 thereof is substantially eliminated and upon the carrier 12 being subjected to sudden jars or jolts each group will shift independently upon the carrier floor, since the groups are not attached thereto and the force imparted to the group, due to the sudden jolt, is checked only by the inertia of its own weight. Thus each coil with its cable stub 21 extending from the upper end of the case 11 is fully protected from damage during transit since the coils within the group cannot move against each other or the coils within another group and any movement of a group thereof upon the carrier is reduced to a minimum.

Upon the loaded carrier 12 reaching its destination the coils may be readily removed therefrom, individually, after cutting the horizontal and vertical straps 35 and 38, respectively, used in the securing of a plurality of coils into the group 10. After being removed from the carrier an individual coil still bound to its skid 13 may be transported to its actual point of installation or removed therefrom, depending on the distance to be traveled to its point of installation, the type of carrier or other considerations. The

bracket 22 is preferably maintained on the case 11 for protecting the cable stub 21 until the coil has reached its point of installation. In some installations the coils are lowered into man-holes, the entrance diameter of which is substantially that of the case 11, for connection to an underground conduit, in which case after cutting the looped strappings 30 to release the coil from its skid 13, the lugs 28 are rotated on the bolts 26 to bring their outer ends within the circumference of the coil case 11 by striking them with a hammer. This movement of the lugs 28 and the subsequent lowering of the coil into the manhole may be accomplished without the removal of the bracket 22, since no portion thereof extends beyond the circumference of the case 11. After being used the skids 13, brackets 22 and lugs 28 may be returned to the manufacturer for further use.

Although the invention has been disclosed in connection with the shipping of a particular article, it is clear that it may have a more general application, and that modifications can be made without departing from the spirit and scope of the appended claims.

What is claimed is:

1. In an apparatus for securing for transportation an article having a greater height than width, a support for the article having a plurality of spaced portions extending beyond the periphery thereof, a plurality of removable lugs arranged around and secured to the upper end face of the article and extending slightly beyond the periphery thereof, and a plurality of looped flexible means applied under tension extending individually around and from one of the lugs to and around one of the spaced extending portions of the support beyond the periphery of the article.

2. In an apparatus for securing for transportation a cylindrical assemblage having a flexible portion extending from the upper end surface of the main body of the assemblage, a removable member extending around and supporting the flexible portion, the member having bifurcated ends which are attached to the adjacent end face of the main body of the assemblage, the member at all portions disposed within the circumference of the assemblage.

3. In an apparatus for securing for transportation an article having an integral flexible portion extending from the upper end of the main body of the article, a removable loop member extending around and supporting the flexible portion of the article, the loop member having bifurcated ends with the furcations thereof extending angularly to the adjacent end of the article and attached thereto.

4. In an apparatus for securing for transportation an assemblage having a greater height than width and provided with a por-

tion extending from the upper end of the main body thereof, a support for the assemblage extending beyond the periphery thereof, a removable member extending around and supporting the outer end of the extending portion and attached at its ends, together with a plurality of lugs, to the adjacent end of the main body of the assemblage, and a plurality of tension members extending from the lugs to portions of the support extending beyond the periphery of the assemblage.

5. In an apparatus for preparing for transportation a loading coil having a cable stub projecting from its upper end, a sliding base adapted to receive the coil and extending beyond the periphery thereof, means for securing the coil to the base, and a looped member removably secured to the upper end of 20 the coil and adapted to confine the cable stub within the lateral extent of the coil.

6. In an apparatus in preparing for transportation a heavy loading coil, a sliding base of greater lateral extent than the coil, a plurality of lugs pivoted to the upper surface of 25 the coil and having portions normally extending beyond the periphery thereof but movable to a position within said periphery, and tension members extending from said 30 portions to the sliding base to secure the coil rigidly to the base.

In witness whereof, I hereunto subscribe my name this 13th day of July A. D., 1928.

ARTHUR LIONEL MANNING.
